UNITED STATES PATENT OFFICE.

HAROUTUN VOSKERCHIAN, OF NEW YORK, N. Y.

COMBINATION CAMEO BROOCH.

Application filed October 19, 1926. Serial No. 142,549.

This invention relates to brooches and has for one of its objects the provision of a compartment in the rear portion of the brooch.

Another object of my invention is the provision of a hinged cover disposed over a compartment in a brooch adapted to be retained in closed position.

A further object of my invention is the provision of a pin for attaching a brooch to a wearer adapted to retain a hinged cover in closed relation to a compartment in the brooch.

In the drawings:

Fig. 1 is a perspective rear view of a brooch embodying my invention;

Fig. 2 is a longitudinal sectional view taken on the line 2—2 of Fig. 1;

Fig. 3 is a front plan view of a brooch showing portions thereof removed for disclosing underlying parts;

Fig. 4 is a transverse sectional view taken on the line 4—4 of Fig. 1;

Fig. 5 is a fragmentary rear view of a brooch embodying my invention;

Fig. 6 is a perspective view of a safety catch for securing the pin of the brooch in locked relation;

Fig. 7 is a perspective view of a modified form of my improved brooch; and

Fig. 8 is a sectional view of another modified form of my improved brooch.

Referring particularly to the drawing:

The numeral 10 designates a short tubular member of oval construction and the numeral 11 designates a peripheral flange comprising ornamental structure mounted on the outer surface 12 of the tubular member 10. A concave partition 14 is disposed in the tubular member 10 intermediate the ends thereof dividing said tubular member into front and rear compartments 15 and 16 respectively. A stone 17, preferably of the type commonly known as cameos, is mounted in the front compartment 15. The front edges 18 of the tubular member 10 are disposed inwardly as indicated at 19 to engage the outer surface of the stone mounting for retaining the latter in the front compartment. The back of the cameo mounting may be formed to conform with the shape of the partition 14 against which it abuts.

An elliptical ring member 20 is disposed in the rear end of the tubular member and is secured thereto by solder in an extended relation with respect to the rear end of said tubular member. The ring 20 is provided

at its upper extremity with a hinge element 21 adapted to co-act with the hinge element 22 mounted on the cover 23 for pivotally attaching said cover to the brooch in position 60 to close the open rear end of the tubular member. The cover 23 is provided with a flange 24 positioned inwardly from the edge of the cover and extending completely around the circumference thereof. A picture 65 may be pasted on the inner surface of the cover if desired. The flange 24 is adapted to recline within the ring 20 and adjacent the inner surface thereof. An extension 26 at the bottom of the cover 20 is provided for 70 facilitating opening thereof.

A pin 27 is pivotally mounted in a bracket 28 rigidly secured to the rear surface of the ornamental flange 11 on one lateral side thereof and is adapted to engage the catch 75 29 mounted on the opposite side of said flange. The details of the catch 29 are shown in Fig. 6 wherein the numeral 30 designates a standard comprising a looped upper end 31. A lever 32 is pivotally mounted in a slot 33 in the standard and is provided at one end with a handle numeral 34 and at the other end with an extension 35 adapted to be positioned in close relation to the open end of the loop 31 for closing the same to 80 prevent accidental disengagement of the pin 27 from the looped member 31 in which the sharpened end portion 36 of the pin is adapted to be disposed.

The brooch may be pinned to a garment 90 by employment of the pin 27 or it may be depended from a chain if desired by attachment of a chain, not shown in the drawings, to the pivotally mounted ring 38 journaled on the pin 39 mounted in the bracket 40. 95

Spaced projections 41 are mounted on the rear surface of the cover 23 in position to be engaged by the pin 27 when the latter is disposed in the loop 31 of the catch 29 for retaining the cover 20 in closed relation. It 100 should be understood that the cover may be retained closed by engagements of the registering depressions 42 and 43 in the ring 20 and the flange 24 respectively and that the cover is locked in closed relation when the pin 27 is held in contact with the spaced projections 41. Thus the pin 27 has the double function of securing the brooch to a garment and holding the cover 23 closed over the open end of the rear compartment 16 110 which may be employed for carrying coins, cosmetics or trinkets such as pins.

In the modified form of my invention shown in Fig. 7, a block 41' provided with a groove 42' is mounted on the cover 23'. The groove 42' is adapted to receive the pin 27' which is pivotally mounted as described in the description of Figs. 1 to 5 inclusive.

The modified form of my invention shown in Fig. 8, comprises a pin 27^a of irregular curvature adapted to contact at spaced points directly with the surface of the cover 23^a as shown, the other elements being identical to those described in connection with the description of Figs. 1 to 6 inclusive.

The pointed end portion of the pin 27^a is formed, as shown in Fig. 8, so as to recline at an inclination to the cover 23^a when both the pin and cover are in closed position, and the catch 29 is adapted to engage the pointed end portion of the pin 27^a for retaining the intermediate curved portions thereof in contact with the cover.

Having thus described and shown an embodiment of my invention, what is desired to be secured by Letters Patent of the United States is:

1. In a brooch, the combination of a tubular member adapted to support at its for-

ward end an ornamental stone, and formed at its rear end with a compartment having an open extremity, a cover pivotally mounted on said tubular member adapted to be disposed over the open end of said compartment, fastening means comprising an irregularly curved pin pivotally mounted on said tubular member adapted to engage said cover at spaced points for holding the same in closed position.

2. In a brooch, the combination with a tubular member having an open extremity, a cover pivotally mounted on said tubular member adapted to be disposed over said open extremity, a pin curved irregularly throughout its length pivotally mounted on said tubular member adapted to engage said cover at spaced points, said pin having a pointed free extremity, and a catch on said tubular member to engage the pointed end portion of said pin for retaining the portions of the pin adapted to engage the cover at spaced points in contact with said cover.

In testimony whereof I have affixed my signature.

HAROUTUN VOSKERCHIAN.
